P. A. WAGNER

REED FOR LOOMS

Original Filed Sept. 23, 1921

Patented July 10, 1923.

1,461,547

UNITED STATES PATENT OFFICE.

PAUL A. WAGNER, OF JERSEY CITY, NEW JERSEY.

REED FOR LOOMS.

Application filed September 23, 1921; Serial No. 502,641. Renewed December 9, 1922.

To all whom it may concern:

Be it known that I, PAUL A. WAGNER, a citizen of the United States, residing at Jersey City, in the county of Hudson and State of New Jersey, have invented a certain new and useful Improvement in Reeds for Looms, of which the following is a specification.

The object of the invention is to provide a reed in which the dents are accurately, uniformly and closely spaced, and which may be easily and economically manufactured.

Another object is to provide means whereby the dent-ends are held in position frictionally in the dent holders during the assembling operation before permanent attachment to such holders and the reed bands, thus facilitating the assembling operation, such means also serving to permit the removal and replacement of worn or defective dents from the finished reed without displacing adjacent dents.

The invention consists in certain novel features of construction by which the above objects are attained, to be hereinafter described and claimed.

The accompanying drawings form a part of this specification and show an approved form of the invention.

Figure 1 is a plan or top view of a portion of one of the dent holders, on a greatly exaggerated scale.

Figure 2 is a corresponding elevation of the grooved face of such holder.

Figure 3 is a vertical section, taken on the line 3—3 in Figure 2.

Figure 4 is an elevation on a smaller scale than the preceding figures, showing a lower corner of a reed with certain portions broken away.

Figure 5 is a vertical section on the line 5—5 in Figure 4.

Figure 6 is a horizontal section, taken on the line 6—6 in Figure 5, and partly in plan view.

Figure 7 is an edge view of a dent-end, on the same scale as Figures 1, 2 and 3.

Figure 8 is a corresponding face view.

Figure 9 is an elevation of the finished reed, on a still smaller scale.

Similar reference numerals indicate the same parts in all the figures.

Referring to the drawings, 10 is one of a pair of holders each a rectangular bar of steel of suitable dimensions, having equally

spaced grooves 11 extending transversely across one face, produced by milling, sawing, or an analogous operation, slightly wider than the thickness of a dent and 60 adapted to receive the dent-ends. The depth of the grooves is preferably the same as the width of the dent.

The dents 12 are provided at their ends with means for frictionally engaging the 65 walls of the grooves with sufficient force to prevent displacement by gravity when inserted in the holders, during the process of assembling. The means shown comprises spring tongues 13 formed integrally with 70 the dent by suitable dies and offset or bent outwardly on one face of the dent, as in Figures 7 and 8, adapted to be compressed when the dent-end is inserted in its groove and thus yieldingly engage the adjacent 75 wall of the groove, as indicated in Figure 4.

The lands forming the grooves 11 are omitted at each end of each holder 10, to form notches in which the end bars 15 are received, and the bands 16 are applied to 80 the holders and end bars, each band having a flange 17 overlapping the ends of the dents in their holders, and the thin strips 18, preferably of the same width as the bands are applied to cover the lands and 85 outer edge faces of the dent-ends.

The whole is soldered by dipping or otherwise and the corners of the reed further strengthened by the usual rivets 19 if desired.

To induce a degree of tensile strain on the dents and thus increase the stiffness of the reed, the holders 10 are each slightly bowed outwardly and oppositely as indicated by the dotted lines in Figure 9, and 95 forced into parallelism by suitable means while the dents are introduced and soldered. The effort to re-assume the bowed condition when released induces the desired longitudinal strains on the dents.

To remove a dent, the solder is softened and the strips 18 removed to permit access to the ends of the worn or defective dent which is then removed and replaced by a perfect dent. The strips 18 are then again 105 applied and the whole permitted to cool and harden. The tongues 13 aid in maintaining the adjacent dents in place during the removal and replacement operation.

Other means than the tongues 13 may be 110 employed to induce frictional engagement of the dent-ends with the grooves of the

holders 10, or the dents may be simply placed in the grooves without such frictional engagement.

I claim:—

- 5 1. In a reed, a holder having grooves therein, dent-ends received in said grooves, and means formed by offsetting a portion of each dent-end for frictionally engaging such end with the walls of its groove.
- 10 2. In a reed, a holder having grooves therein, dent-ends received in such grooves, and projecting tongues formed integrally with said dent-ends for frictionally engaging such ends with the walls of such grooves.
- 15 3. In a reed, a pair of separated holders each having grooves formed therein, and bowed outwardly and oppositely, and a series of dents secured in such grooves while said holders are forcibly held in parallelism, whereby said dents are strained longitudinally when said holders are released.
- 20 4. In a reed, a pair of separated holders

each having equally spaced grooves therein, a series of dents having their ends secured in such grooves, end bars received in notches 25 at the ends of said holders, and bands each secured along the plain face of each of said holders and to said end bars, and having a flange overlapping the ends of said dents and end bars.

30 5. In a reed, a pair of separated holders each having equally spaced grooves therein, a series of dents having their ends secured in such grooves, end bars received in notches 35 at the ends of said holders, bands each secured along the plain face of each of said holders and to said end bars, and having a flange overlapping the ends of said dents and end bars, and strips each secured to the grooved face of each of said holders and to 40 said end bars.

In testimony that I claim the invention above set forth I affix my signature.

PAUL A. WAGNER.
